Dec. 1700

E. Elmer Jr. of Lowell Mass.
assignor to
The Lowell Manufacturing Company
Letters Patent No 1700 United Dec 16, 1862

The schedule referred to in these Letters Patent and making part of the same,

To all whom it may concern;

Be it known that I, E. Elmer Jr. of Lowell in the County of Middlesex and State of Massachusetts have invented or produced an improvement on a design for Carpets or other fabrics, of which the following is a full, clear and exact description, reference being had to the accompanying drawings, making part of this specification.

Drawing No 1. is the improved design.

Drawing No 2. is a pattern of paper hanging.

Extending from corner A. to corner B. in the 1.,
is a broad network composed of octagons, diamonds, small crosses & blocks, lines and dots, arranged as shown in the drawing.

The filling up of the sections of the bands 1. and 2. alternates between lines and dots.

The outlines of the remaining parts are copied from corresponding parts of Drawing No 2.

The colors employed for the different portions of the design, may be varied to suit the taste and wish of the manufacturer.

Claim.

What I claim as my invention and desire to secure by letters patent, is the improvement in the design or pattern, for carpets or other fabrics, herein set forth.

I disclaim all parts of Drawing No 1. which are copied from Drawing No 2. and not set forth in the specification.
